UNITED STATES PATENT OFFICE.

JOSEPH A. MUDD, OF CHICAGO, ILLINOIS.

TEMPORARY BINDER.

1,026,277.

Specification of Letters Patent.

Patented May 14, 1912.

Application filed October 12, 1909. Serial No. 522,262.

To all whom it may concern:

Be it known that I, JOSEPH A. MUDD, a citizen of the United States, residing at Chicago, in the county of Cook and State of Illinois, have invented a new and useful Improvement in Temporary Binders, of which the following is a specification.

My invention relates particularly to temporary binders provided with means for preventing unauthorized removal of leaves therefrom, such as loose-leaf ledgers; and my primary object is to provide in binders of the type indicated improved means for operating and locking the binder through the medium of a single key.

The invention is illustrated in the preferred embodiment thereof in the accompanying drawing, in which—

Figure 1 represents a plan view of the operative portion of a loose-leaf binder with the key thereof detached; Fig. 2, a sectional view on an enlarged scale, the section being taken as indicated at line 2 of Fig. 1; Fig. 3, an enlarged horizontal sectional view taken as indicated at line 3 of Fig. 2; and Fig. 4, a broken perspective view showing the key-controlled and actuated barrel employed, a portion of the screw-rod employed, and a connecting member joining the barrel and screw-rod, the parts being shown disconnected.

In the construction illustrated, A, A¹ represent the clamping members or jaws of a loose-leaf binder; A², the back upon which said clamping members are transversely slidably, said back being provided at its extremities with guides A³; A⁴, telescopic binding-posts joining the edge portions of the clamping members A, A¹; A⁵, mechanism serving to open and close the binder, said mechanism including a right and left threaded screw-rod A⁶ journaled on the binder-back; B, a key-controlled device through the medium of which the screw-rod A⁶ may be actuated; and B², a connecting member joining the barrel of the device B to the screw A⁶.

The binder may be of any approved construction. In the construction shown, the rod A⁶ is journaled on the back A² and confined against longitudinal thrust at the point 1 in a well understood manner. Said rod extends longitudinally of the binder-back practically from one end of the binder to the other. The mechanism A⁶ includes

pairs of links 2 which have pivotal connection in the usual manner with the clamping members and with nuts 3 mounted on the screw-rod A⁶. It will be understood that when the rod A⁶ is rotated in one direction, 60 the binder-frame will be opened or expanded; and when the rod A⁶ is rotated in the opposite direction, the binder-frame will be contracted, the clamping members sliding transversely with relation to the binder-back. 65

The device B preferably comprises a block 4 which is screwed to the inner surface of the binder-back near one end thereof, said block 4 having a bore 5 in alinement 70 with the adjacent end of the rod A⁶; a key-controlled and actuated barrel 6 extending through the bore in the block 4 and provided with a circumferential groove 7 which receives a pin 8 adapted to prevent longitudinal movement of the barrel with relation to the block 4; and key-retracted barrel-locking devices 9 connected with the block 4 and barrel 6. Each guide A³ comprises a removable guide-plate 10 which extends transversely across the end portion of the binder-back, being spaced with relation thereto to enable the flanges 11 of the clamping members to pass between them and the back. The block 4 is located beneath one of the plates 10, and is secured between said plate and the back by means of screws 12. 80

The barrel 6 is rotatable in the bore 5, but normally locked against rotation by the device 9. The barrel 6 is partially severed longitudinally by a key-receiving slot 13 adapted to receive a special key. There are a series of the locking devices 9, three of said devices being shown. Each device 95 comprises a plunger 14 and a ball 15 received in a transverse bore 16 with which the key-barrel is provided; and a plunger 17 and spring 18 received in a registering bore 19 with which the block 4 is provided on one side of the bore 5. The springs 19 are held in place by a slide 20 connected with one lateral wall of the block 4. The bore 16 intersects the key-slot 13. In Fig. 3, the key is shown partially inserted, thereby lifting the ball and innermost plunger 14 of the first device 9 and raising the plunger 17 substantially above the wall of the bore 5. In the normal position, the plungers 17 lock the key-barrel against rotation; and when the 100 105 110

key is inserted, the balls are elevated sufficiently to enable the barrel to rotate when the key is turned.

The device B² comprises a short sleeve 21 having one end journaled upon the reduced end 22 of the key-barrel and the other end journaled on the reduced end 23 of the rod A⁶. The cylinder, or sleeve, 21 is provided with a pair of circumferentially-extending slots 24 and 25 which are located near opposite ends of the sleeve and are staggered with relation to each other. That is to say, the slots 24 and 25 are cut through opposite walls of the sleeve, and each slot preferably extends through somewhat more than a half of the circumference of the sleeve. The extension 22 of the key-barrel is provided with a short lateral stud 26 adapted to work in the slot 24 of the sleeve 21; and the extension 23 of the rod A⁶ is equipped with a short lateral stud 27 adapted to work in the slot 25. The extremities of the slots 24 and 25 afford stops which co-act with the studs 26 and 27.

From the foregoing description, it will be understood that the sleeve 21 may rotate with relation to the rod A⁶ somewhat more than 180°, and the key-barrel 6 may rotate with relation to the sleeve 21 through somewhat more than 180°. It follows that the key-barrel may rotate with relation to the rod A⁶ through an angle of somewhat more than 360°, i. e., somewhat more than a full rotation. This construction permits the key-barrel to be returned to a given point to enable the key to be withdrawn, regardless of the point at which the rotation of the rod A⁶ may cease in the operation of closing the clamping members A and A¹ upon the leaves of the ledger. It will be understood, therefore, that the key B¹ may serve as a means for turning the rod A⁶ through the medium of the key-barrel 6 and sleeve 21, and after the clamping members have been sufficiently tightened upon the

leaves to prevent their withdrawal, the key may be turned backward to the point where the perforations 16 register with the perforations 19, when the key may be withdrawn. Inasmuch as the key-barrel 6 is normally locked and cannot be released except by means of a proper key, it will be obvious that it will be impossible for unauthorized persons to open the binder to permit withdrawal of the leaves therefrom. The connecting device joining the key-barrel to the rod A⁶ is of simple, cheap and durable construction. The connection between the tubular connecting member, the key-actuated barrel and the threaded rod may be described as a telescopic and lost-motion connection.

The foregoing detailed description has been given for clearness of understanding only, hence no undue limitation is to be understood therefrom.

What I regard as new, and desire to secure by Letters Patent, is—

In a loose-leaf binder, the combination with leaf-holding and clamping devices and actuating means therefor, including a right and left threaded actuating rod, of a key controlled and actuated rotary member, and a tubular connecting member journaled on the inner end of said rotary member and the adjacent end of said actuating rod, said tubular connecting member being provided with a pair of substantially circumferential slots, and laterally projecting pins carried by said rotary member and said rod and working in said slots, whereby the key may, after serving to actuate said clamping devices, be turned back to one point for withdrawal regardless of the position of the clamping devices.

JOSEPH A. MUDD.
